SIMON LAKE, OF MILFORD, CONNECTICUT.

METHOD OF AND APPARATUS FOR FORMING CONCRETE STRUCTURES.

Application filed March 1, 1921. Serial No. 448,838.

To all whom it may concern:

Be it known that I, SIMON LAKE, a citizen of the United States, residing at Milford, in the county of New Haven and State of Connecticut, have invented a certain new and useful Improvement in Methods of and Apparatus for Forming Concrete Structures, of which the following is a full, clear, and exact description:

10 It is well known to those familiar with the art of working concrete that to secure a perfect bond between the various parts of a concrete structure it is important to have the concrete applied to the forms or molds continuously, otherwise imperfect union of the parts will result and the structure will be materially weakened. Also, pressure has been found to increase the density and strength of concrete if applied while the 20 mixture is plastic and before it has begun to set.

It has been found advantageous, especially where metal reinforcing members are used, to hasten the drying of the concrete by artificial means so as to prevent rusting of the reinforcing members and subsequent weakening of their bond with the surrounding concrete. This protection of the reinforcing members, and also of the concrete itself is enhanced by the application of waterproofing material to the structure while still plastic and preferably simultaneously with the application of artificial heat.

The object of my invention is to provide a 25 method of and apparatus for forming concrete structures or bodies whereby the concrete may be molded under pressure and all excess air and moisture expressed therefrom and removed and the body subsequently and 40 while still in a plastic state subjected to the action of artificial heat and, if desired, the action of a waterproofing and pore-filling agent.

The invention consists in a method of and 45 apparatus for forming concrete bodies comprising the mixing of the concrete, extraction of air therefrom, forcing the thus densified and homogenized mixture into a mold by pressure, extraction of excess water from the concrete while in the mold by the continued application of pressure and suction and subsequent heating and drying of the thus-formed concrete body in the mold; the concrete mixture being once freed from 55 trapped air being subsequently so handled as to preclude the possibility of air being again

trapped in it while it is undergoing molding, all as I will proceed now to explain and finally claim.

In the accompanying drawings illustrating the invention in the several figures of which like parts are similarly designated, Figure 1 is a sectional elevation showing an embodiment of my apparatus whereby my method may be carried out. Fig. 2 is a fragmentary longitudinal sectional view showing one end of my mold with its core and connections. Fig. 3 is a transverse section through the mold alone taken in the plane of line 3—3, Fig. 2. Fig. 4 is an elevational view of the core on a reduced scale. Fig. 5 is an enlarged transverse section of the core of Fig. 4. Fig. 6 is a view similar to Fig. 5 but showing a modification in which the core is constructed wholly of metal. Fig. 7 is a central longitudinal section of a telegraph pole such as may be produced by my method and apparatus. Fig. 8 is an enlarged fragmentary detail view showing the method of reinforcing the pole of Fig. 7. Fig. 9 is a section taken on line 9—9 of Fig. 8. Fig. 10 is a view showing the mode of assembling the main reinforcing members.

Referring particularly to Fig. 1, the apparatus comprises a concrete mixer 1, mounted upon and supported by a tank 2, hereinafter called the pressure tank. Extending through the tank 2 and into the mixer 1 is a shaft 3 driven by suitable gearing 4 and carrying two stirrers, one of which 5 is located in the mixer and the other 6 in the pressure tank. Communication between the mixer and pressure tank is afforded by means of a tube 7 controlled by means of a gate valve 8. Suitable hoppers or chutes 9, 10 and 11 may be provided above the mixer 1 for the purpose of feeding cement, sand and gravel thereto.

The mold of my apparatus (see Figs. 1, 2 and 3) comprises four sections 12, adapted to be bolted together upon spacer pieces 13 whereby channels 14 are formed extending longitudinally of the mold and providing means whereby easy flow of the concrete may be attained. The bottom spacer piece 13 is pipe-tapped and provided with a pipe 15 which is connected through a cleaning trap 16 (Fig. 1) with a tube 17 communicating with the bottom of the pressure tank and controlled by a gate valve 18. The top spacer piece 13 (Fig. 2) is provided with a longitudinal groove 19 and faced with a strip of filtering material 20, such as will al-

low water and air to pass through it but will not allow the passage of other ingredients of the concrete. This spacer piece is also pipe-tapped and provided with a pipe 21 communicating with the groove 19 and with the exhaustion side of a compression-exhaustion pump 22 (Fig. 1) through pipes 23 and 24, settling tank 25 and pipe 26. The settling tank 25 is provided with a sight glass 27 having a drain cock, for a purpose later appearing. The ends of the mold are closed by heads 29 having bearing members 30 in which are supported trunnions 31 arranged in the ends of a core 32 and serving to support the core axially of the mold.

The core 32 may be constructed in a variety of ways so long as provision is made for heating it internally. I have shown in Figs. 2, 4, 5 and 6, two forms of core adapted to the purpose of my invention. In Figs. 2, 4 and 5 the core is shown as comprising a central member 33, preferably of wood, and provided with a plurality of longitudinal grooves 34, the whole being covered with a metallic sheath 35 which in addition to forming a casing therefor provides spaces 36 at the ends thereof communicating with the grooves 34, and into these spaces lead steam inlet and drain pipes 37 and 38, respectively, whereby steam may be circulated through the grooves 34, and the core thereby heated. In Fig. 6 the core is shown as made entirely of metal, and comprises an inner tubular member 39 and an outer tubular member 40 forming between them an annular steam space 41.

Again referring to Fig. 1, it will be seen that the pump 22 is, in addition to its connection with the mold, connected also with the pressure tank 2 through a pipe 42 provided with a two-way valve 43 which communicates also with a compressed air reservoir 44 by means of pipe 45. This reservoir 44 receives its compressed air through pipe 46 from the compression side of pump 22. Communication between the mold and pump 22 is controlled by a valve 47, and an automatic air inlet valve 48 is provided so that air may be supplied to the pump after all air has been exhausted by it from the mold.

Referring now to Figs. 7 to 10 inclusive, wherein a concrete telegraph pole, such as may be constructed by my method and apparatus is shown, a reinforcing framework is provided composed of longitudinal rods 49 surrounded at intervals throughout their length by rings 50 to which they are welded or otherwise tied. Around the framework thus constructed wires 51 may be spirally wound to form a sort of basket-work. If desired, wire cloth or coarse wire mesh may be substituted for the wires 51.

It will be observed by reference particularly to Figs. 8 and 9 that the channels

14 of the mold form ribs 52 on the side of the pole, and in these ribs I prefer to form sockets 53 to provide means whereby a lineman may climb the pole by inserting his climbing spurs therein. If desired, a cap 54 may be inserted in the top of the pole to exclude water from the interior thereof.

The method is carried out as follows:— First the core 32 is covered with some fusible material, such as paraffin. I prefer the use of paraffin for the reason that it is not sticky and leaves the core clean when removed therefrom by heat. Then a strip of ordinary tar or building paper 55 (Fig. 5) is wrapped completely around the core throughout its length and this covering of paper is coated with a generous application of tar or pitch or the like fusible waterproofing material. The core is then slipped inside of the reinforcing basket and by means of its trunnions 31 supported in the bearing members 30 of the heads 29 of the mold. The mold is then completely assembled around the core and reinforcement, suitable packing material or gaskets being interposed, if necessary, between the sections 12 and spacers 13 to form an airtight chamber of the mold. The mold is supported in operative relation to the casting apparatus upon stanchions 56, and the various pipes are connected with it. The valve 8 being closed, a charge of concrete ingredients is run into the mixer 1 from the hoppers 9, 10 and 11 and water added thereto and the shaft 3 rotated to operate the stirrers 5 and 6. Also the pump 22 is put in operation and the valve 43 adjusted so as to establish communication between the exhaustion side of the pump and tank 2, valve 47 being meantime closed, whereby the pump will exhaust the air from tank 2 and will furnish compressed air to reservoir 44.

After the concrete has been sufficiently mixed by mixer 1 the valve 8 will be opened and the concrete will be sucked into tank 2 by reason of the vacuum therein produced by the pump 22, and when sufficient concrete is run into tank 2 to charge the mold, the gate valve 8 is again closed and the suction continued during agitation of the concrete by stirrer 6 until all of the trapped air has been removed. Now, the valve 43 is adjusted so as to cut off suction from tank 2 and valve 47 is opened to create a vacuum in the mold. As soon as the air has been withdrawn from the mold, the mixing is stopped and valve 43 is adjusted to admit compressed air from reservoir 44 to tank 2 and gate valve 18 is opened, whereby the concrete is forced, by the pressure of the air, into the mold. As all air has been extracted from tube 17 and from the mold, it will be apparent

that no air can come in contact with the concrete. The vacuum pump 22 is kept running, and when the mold is filled, the great pressure caused by the air in tank 2 will cause any excess moisture in the concrete to be expressed through the filter material 20, and this water will be sucked out through pipe 21 and deposited in settling tank 25, from which it may be withdrawn through the drain cock of glass 27 as required. The operation of the pump 22 is now stopped, and the concrete body in the mold allowed to get its initial set. Then the top of the mold is removed and the body exposed, and to hasten its hardening steam is allowed to circulate through the core through pipes 37 and 38.

I have found that concrete castings may be rapidly dried out without causing cracks in the casting if the heat is applied gradually to the interior of the mass so as to give a gradually increasing temperature until the entire mass becomes dry, at which time it has attained a considerable degree of hardness and tensile strength and has also become thoroughly bonded to its reinforcement.

The heating of the core causes its paraffin coating to fuse and admits of the subsequent withdrawal of the core with comparative ease.

On the casting becoming dry it is lifted from its mold and while still warm a coating of any suitable waterproofing or enameled compound may be applied to it. At this time the pores of the concrete adjacent to the surface are still open, due to its expansion under heat, and the waterproofing material therefore penetrates into these pores, and when shrinkage takes place the surface is both waterproof and air-proof, and if a non-conducting waterproofing material is used, it also makes an excellent non-conductor of electric currents. Heating up of the core has also caused the fusible compound surrounding the core to penetrate the interior surfaces of the body with a waterproofing compound, so that if "sweating" should occur on the interior of the casting, it cannot penetrate to the metal reinforcement, thus insuring long life to the structure.

While I have described my method and apparatus as adapted to the manufacture of a concrete telegraph pole, it is to be understood that it is equally well adapted to the manufacture of various other concrete structures. Furthermore, it is conceivable that various changes may be made in the method and apparatus without departing from the spirit of the invention or the scope of the following claims.

What I claim is:—

1. A method of forming concrete bodies, which consists in forming a mold, exhausting the air therefrom, forcing concrete un-

der pressure into said mold, continuing such pressure after the mold is filled to express the surplus moisture from said concrete, withdrawing such surplus moisture from said mold, and applying heat to the concrete body to hasten its drying.

2. A method of forming hollow reinforced concrete bodies, which consists in forming a mold, supporting a core in said mold, exhausting the air from said mold, forcing concrete under pressure into the space within said mold surrounding said core, extracting the surplus moisture from said concrete and withdrawing such moisture from the mold, and applying heat to the interior of said concrete body in the mold by a heating fluid introduced through the medium of said core.

3. In an apparatus for forming concrete bodies, a mold, a concrete mixer provided with a concrete receiving pressure tank connected with said mold, means connected with said mold for withdrawing the air therefrom, and means for establishing pressure in said pressure tank to force the concrete therefrom and into said mold, the means for withdrawing air from the mold being thereafter actuated to withdraw excess moisture from the pressure-introduced concrete in the mold.

4. In an apparatus for forming concrete bodies, a mold, a concrete mixer, a pressure tank adapted to receive concrete from said mixer, connections between said tank and mold, a reservoir for the storage of air under pressure, a compression-exhaustion apparatus, connections between said compression-exhaustion apparatus and said tank reservoir and mold, and valves for controlling the operation of said compression-exhaustion apparatus relative to said tank reservoir and mold for the purpose specified.

5. In an apparatus for forming concrete bodies, a mold, a concrete mixer, a compression-exhaustion pump, a pressure tank having valved connection with said concrete mixer, mold and pump, a storage reservoir adapted to receive and store air under pressure from said pump and connected with said pressure tank, an air intake conduit for said pump communicating with said mold, and a settling tank interposed in said conduit, whereby concrete may be forced under pressure into said mold, from which the air has been exhausted, and therein subjected to pressure to express surplus moisture and this moisture withdrawn and deposited in the settling tank as specified.

In testimony whereof I have hereunto set my hand this 28th day of February A. D. 1921.

SIMON LAKE.
